Inventor:

Charles Kemp,

By his Attorney, Geo. W. Math

UNITED STATES PATENT OFFICE.

CHARLES KEMP, OF NEW YORK, N. Y.

ELECTRICAL CIRCUIT CLOSER.

Application filed May 5, 1924. Serial No. 711,014.

To all whom it may concern:

Be it known that I, CHARLES KEMP, a citizen of the United States, and a resident of the borough of Manhattan, city, county, and State of New York, have invented certain new and useful Improvements in Electrical Circuit Closers, of which the following is a specification.

While adapted for general use in connection with electric circuits for various other purposes, my improved circuit closer is designed primarily and specially for employment as a component part of a burglar alarm system in which my circuit closer is incorporated in such manner as to actuate an alarm whenever the electric circuit involved is closed thereby.

To this end the invention consists in the specific combination and arrangement of constituent parts and appurtenances herein described and claimed, whereby I positively attain instantaneous results and efficiency, in that my plural contact circuit closer device is operative in several directions, i. e., transversely, and rectangularly, as related to each other; or, in other words, the device has three closure contact surfaces co-related to each other, the switch arm being held normally in medial position, and out of engagement with either of the three contactual surfaces, by means of a ligature, the disturbance, severance, or release of which will result in the closure of the electric alarm circuit at one contact or the other, as the case may be, and as hereinafter fully set forth, whereby an effective supersensitive detective alarm is provided for the protection of any space or area, enclosed or otherwise, exposed to danger of surreptitious entrance or unlawful intrusion.

In the accompanying drawings I illustrate, by way of exemplification, a plural contact surface electric circuit closer device embodying the essential features of my invention in practical and operative relationship, although I do not confine myself to the identical form and construction of parts shown, since modifications and equivalent mechanical expedients may be resorted to without departing from the spirit and intent of my invention in this respect.

With this understanding:

Fig. 1, is a side elevation of my plural contact electric circuit closer, set for use with

the drop latch held extended by the detective ligature, and the switch lever in normal medial position;

Fig. 2, is a front elevation of my device, with the parts in the relative positions shown in Fig. 1;

Fig. 3, is a side elevation like unto Fig. 1, but showing the detective ligature severed, and the latch dropped into engagement with the medial bridge contact surface;

Fig. 4, is a central vertical section taken upon plane of line 4—4 Fig. 2;

Fig. 5, is a front view like unto Fig. 2, showing the switch lever released from normal medial position and held by spring pressure against one of the side contact surfaces;

Fig. 6, is a rear elevation of the base plate, etc. of my improved circuit closer.

B, represents the base plate of my device on which the other parts are mounted, said base B, being made of insulating material, and being adapted, as by the countersunk screw holes b, b, for attachment to any convenient stationary support.

F, is a fulcrumed screw post electrically connected by means of the wire t, with the electric circuit terminal T, as shown more particularly in Fig. 6, of the drawings, the other electric circuit terminal post T', being connected in turn by the wire t', with the electrical contact bridge plate C, the latter being rigidly secured to the base B, by screws c, c, or equivalent means. Thus the said electrical contact bridge plate consists essentially of the end flanges c', c', for engagement with the aforesaid attachment screws c, c, and of the side members c², c³, and span or medial member c⁴, the said side members c², c³, and span c⁴, constituting independent electric contactual surfaces as hereinafter set forth.

Fulcrumed on the screw F, is the pivotal link s, forming part of the switch lever S, and to which the circuit closer s', is articulately connected, as will be understood by reference more particularly to Figs. 2, 4 and 5, of the drawings.

A spring s^x, attached at one extremity to the circuit closer s', and at the other to the base B, tends constantly to draw and hold said circuit closer s', of the switch lever S, against the side contact member c², as shown in Fig. 5, of the drawing, thereby

closing the electric circuit e, e , in which the alarm device (not shown) is interposed in a manner well known in the art.

Normally the switch lever S , is held out of contact with the side member c^2 , by means of a snap fastening of well known or suitable character, that shown in the drawing by way of exemplification consisting of a so called "glove fastening" catch comprising a socket a , and an expansive button a' , fitting therein, the button a' , being preferably attached to the upper extremity of the circuit closer s' , and the socket a , being embedded in the base B , although it is obvious that an alternative arrangement of the snap parts named might be resorted to, and that equivalent mechanical expedients might be substituted with like results in this respect, the essential feature being an easily detachable connection between the base and said circuit closing member s' , of the switch lever S .

The drop latch D , is pivotally connected to the upper end of the switch lever S , and is of sufficient length to reach to and contact with the span section c^3 , of the bridge plate C , as shown in Fig. 3, when not otherwise supported, as by the ligature L , when taut is to hold said drop latch D , in approximately horizontal position against the resistance of the snap fastening a, a' , by which the switch lever S , is held in normal medial position as shown in Figs. 1 and 2 of the drawings, and for this reason, in the practical use of my device said ligature L , is stretched across the area or space to be safeguarded.

For instance in Fig. 1, the ligature L , shown as broken away medially, is supposed to be stretched across a space or passageway that would necessarily be traversed by an intruder, one end of said ligature L , being attached to a wall W , or other appropriate stationary part, and the other to the free end of the drop latch D . If the intruder is cautious, and cuts the ligature L , the drop latch D , will be released, and will fall against the span c^4 , of the circuit bridge plate C , thereby closing the electric circuit and actuating the alarm interposed therein. If, however, the ligature L , is not observed by the intruder and he presses against same, the snap fastening a, a' , will be disengaged, releasing the switch lever S , so that it will be shifted and pulled against either the side contact c^2 , or the side contact c^3 , according to the direction of the stress exerted upon the ligature L , thereby, in either case, effecting closure of electrical

alarm circuit. In either event the spring s^x , upon opportunity, will insure the engagement of the switch lever S , with the contact c^2 , thereby effecting continuation of the alarm until the switch lever S , is withdrawn therefrom and relocked in neutral position.

My plural circuit closer is an essentially super-sensitive "trap" device for the detection of the presence of intruders within the area protected thereby, in that any disturbance of the ligature L , will positively close the electric circuit and actuate the alarm connected therewith.

I have herein shown and described my circuit closure device as of triple character in so far as the number of electrical contactual surfaces is concerned, and it is obvious that in doing so I have established my right to claim a plurality of opposed contactual surfaces in conjunction with my medially positioned switch arm of special construction, and with a controlling ligature, said combination of elements being operatively related, substantially as herein set forth.

What I claim as my invention and desire to secure by Letters Patent, is:—

1. An electric circuit closer device of the character designated, comprising a stationary contact member connected with an alarm circuit terminal and formed with a plurality of contactual surfaces, a fulcrumed switch lever connected with the other terminal of the electrical alarm circuit, snap fastening means for holding said switch lever in normal position, a drop latch pivotally attached to said switch lever, a ligature connected with said drop latch, and means for holding said ligature taut, substantially in the manner and for the purpose set forth. 100

2. An electric circuit closer device of the character designated, comprising a stationary contact member connected with an alarm circuit terminal and formed with a plurality of contactual surfaces, an articulated fulcrumed switch lever connected with the other terminal of the electrical alarm circuit, snap fastening means for holding said switch lever in normal position, a drop latch pivotally attached to said switch lever, a ligature connected with said drop latch, and means for holding said ligature taut, substantially in the manner and for the purpose set forth. 110

CHARLES KEMP.
